CLAIM

The ornamental design for a synthetic foam pillow, as shown and described.

DESCRIPTION

FIG. 1 is a top side perspective view of a synthetic foam pillow, showing our new design;

FIG. 2 is an end view thereof, the opposite end being substantially identical;

FIG. 3 is an enlarged detail view of fragment 3 in FIG. 2; FIG. 4 is a front elevational view thereof, the rear being substantially identical; and,

FIG. 5 is a top plan view thereof, the bottom being substantially identical.

The conical pattern in FIGS. 1, 4 and 5 is shown fragmentarily for ease of illustration but is understood to extend continuously throughout.
